UNITED STATES PATENT OFFICE

ELMER E. GULLION, OF KOKOMO, INDIANA

WINDOW-SHADE HANGER

Application filed June 13, 1928. Serial No. 285,160.

This invention aims to provide a simple means whereby a shade bracket may be mounted adjustably on a window frame and to provide novel means whereby both a shade bracket and a curtain pole support may be mounted on a window frame.

It is within the province of the disclosure to improve generally and to enhance the utility of devices of that type to which the invention appertains.

With the above and other objects in view, which will appear as the description proceeds, the invention resides in the combination and arrangement of parts and in the details 15 of construction hereinafter described and claimed, it being understood that changes in the precise embodiment of the invention herein disclosed, may be made within the scope of what is claimed, without departing from 20 the spirit of the invention.

In the accompanying drawings:—

Figure 1 shows in front elevation, a device constructed in accordance with the invention;

25 Figure 2 is cross section on the line 2—2 of Figure 1;

Figure 3 is a section on the line 3—3 of Figure 1;

30 Figure 4 is a front elevation showing a modified form of the invention;

Figure 5 is a section on the line 5—5 of Figure 4;

Figure 6 is a section on the line 6—6 of Figure 4;

35 Figure 7 is an elevation showing another modification;

Figure 8 is a section on the line 8—8 of Figure 7;

Figure 9 is a fragmental longitudinal section 40 showing a modification.

In Figures 1, 2 and 3, there is shown a base which, as a whole, is marked by the numeral 1. The base 1 is fashioned from a single piece of resilient metal bent upon itself 45 as at 2, at one end, to form a front 3 and a back 4, the front and the back being of substantially the same area. In the back 4 there is a plurality of transverse seats 5, in the form of grooves. The front 3 is supplied 50 with a longitudinal opening 6.

The numeral 7 marks a shade bracket including a foot 8 and an arm 9 disposed at right angles to the foot. The foot 8 is located between the front 3 and the back 4 of the base 1, the front 3 being offset as at 10 55 to accommodate the foot 8 of the shade bracket. The arm 9 of the shade bracket extends outwardly through the longitudinal opening 6 in the front 3. The foot 8 of the shade bracket 7 has a rib 11 extended entirely across the foot and adapted to be received in any of the seats 5. In this way, the shade bracket 7 can be adjusted lengthwise of the base 1. Securing elements 12, such as screws, connect the front 3 and the back 4 of the base 1 with the window frame (not shown). Securing elements 14, such as screws pass through the front 3 and the back 4 of the base 1 near to the free ends of the parts 3 and 4. 60 65 70

When the securing elements 12 and 14 are tightened down, the front 3 of the base will be held against the foot 8 of the shade bracket 7 with sufficient force so that the rib 11 on the foot 8 of the shade bracket 7 will be held in any of the seats 5. By loosening the securing elements 14 a little, the front 3 of the base can be sprung apart from the back 4, and when this has been done, the shade bracket 7 can be shifted along to any desired 80 85 position. The curtain pole support is in the form of a right angle hook 15 extended through an opening 16 in the front 3. Any desired means may be supplied for attaching the hook 15 to the back 4. In Figure 2 the aforesaid means is represented by the riveting at 17 of the rear end of the hook 15 into the back 4. An aperture 16 is of sufficient size so that the free end of the front 3 can move in and out along the bottom portion of 90 the hook 15 when the screws 14 are loosened, as has been hereinbefore described, to permit an adjustment of the shade bracket 7 lengthwise of the base 1.

In Figures 5, 4 and 6, parts hereinbefore 95 described have been designated by numerals previously used with the suffix "a".

The modification contemplated consists in forming seats 18, preferably in the form of round holes, in both the front 3 and the back 100

4^a of the base 1, the foot 8^a of the shade bracket 7^a having lugs 19, adapted to fit closely in the holes 18. In this form of the invention, moreover, the curtain pole support 15^a is not riveted to the back, as shown at 17 in Figure 2. Rather, the means for securing the hook 15^a is in the form of a plate 20 to which the screw 15^a is riveted, as shown at 21 in Figure 6, the plate 20 being disposed between the right hand ends of the front 3^a and the back 4^a of the base 1^a. The securing elements 14^a pass through the front 3^a and the back 4^a, and through the plate 20 of the curtain pole support 15^a, also.

15 In Figures 7 and 8, parts hereinbefore described have been designated by numerals previously used with the suffix "b". In this form of the invention, the front 3^b has openings 22, the back 4^b having openings 23. The 20 openings 22 are larger than the openings 23 and are smooth, whereas the openings 23 are threaded. The lugs 19 of Figures 4 and 5 are replaced by screws 24 which turn freely in the openings 23 of the front 3^b, the screws 25 being threaded into the back 4^b. The screws 24 pass through the foot 8^b of the shade bracket 7^b.

30 The screws 24, of course, may be shifted to occupy any of the cooperating openings 22-23. The curtain pole support or hook 15^b may be mounted in place either as shown in Figure 4, or as shown in Figure 2.

35 In Figure 9 of the drawings, parts hereinbefore described have been designated by numerals previously used with the suffix "c". The form delineated in Figure 9 is much like the form shown in Figure 3, the modification consisting in forming transverse internal 40 grooves or seats 25 in both the front 3^c and the back 4^c, the foot 8^c of the shade bracket 7^c having oppositely projecting ribs 26 on both of its surfaces, the ribs 26 being adapted to be engaged in the seats 25 to afford a secure hold.

45 What is claimed is:—

1. A device of the class described, comprising a base including a front and a back, the front having an elongated opening, a shade bracket including a foot located between the front and the back, and an arm extended outwardly through the opening, means for holding the shade bracket in adjusted positions longitudinally of the base, a securing element engaging the front and the back at one end of the base, a curtain pole support, and means for mounting the curtain pole support, the front having an aperture through which the curtain pole support passes, the aperture being of such size as to 50 permit the front to move along the curtain pole support, away from the back, when the securing element is loosened for the purpose of shifting the shade bracket with respect to the base.

65 2. A device of the class described, com-

70 prising a base formed of a single piece of material turned upon itself at one end of the base to form a front and a back, the front having an elongated opening, a shade bracket including a foot located between the front and the back, and an arm extended outwardly through the opening, means for holding the shade bracket in adjusted positions longitudinally of the base, a securing element 75 engaging the front and the back at one end of the base, a curtain pole support, and means for mounting the curtain pole support, the front having an aperture through which the curtain pole support passes, the aperture being of such size as to permit the front to move along the curtain pole support, away from the back, when the securing element is loosened for the purpose of shifting the shade bracket with respect to the base.

80 In testimony that I claim the foregoing as my own, I have hereto affixed my signature.
